HAIR WAVING OR CURLING ROD

Vincent N. Nicosia, Houston, Tex.

Application September 30, 1933, Serial No. 691,706

13 Claims. (Cl. 132—33)

This invention relates to hair wavers or curlers and is an improvement upon my Letters Patent No. 1,900,126, March 7, 1933.

The primary object of this invention is to provide a device of this type wherein the rod is pivotally connected to the hair clamp thereby to enable the rod to be disposed at an incline to the clamp during winding of the hair thereon so as to facilitate the winding operation, enabling same to be effected more easily and quickly, and further to effect automatic movement of the rod to a position at substantially right angles to the clamp by the act of winding the hair on the rod.

A further object of the invention is to provide a clamp which has a drip cup formed therein, combined with a wrapper that is wound about the hair which is curled on the rod, and which has an absorbent portion that projects within the cup so as to absorb any products of condensation resultant from steaming of the hair.

The invention further aims to provide improved means for protecting the scalp from burns.

Still further the invention aims to provide an improved device for giving an upper right croquignole wave.

Still further the invention aims to provide an improved type of clamp for the hair, which is of simplified and economical construction and which affords a range of adjustment dependent upon the size of the curl or wave, and to also provide for ventilation between the clamp and the scalp.

In the drawings:

Fig. 1 is a side elevation of the invention showing in dotted lines the inclined position of the rod at the beginning of the hair wrapping operation thereabout;

Fig. 2 is a section on line 2—2 of Fig. 1;

Fig. 3 is a section on line 3—3 of Fig. 2;

Fig. 4 is a section on line 4—4 of Fig. 2;

Fig. 5 is a bottom plan view of the clamp;

Fig. 6 is a side elevation, partly broken away and in section of a form of the invention for use in croquignole waving;

Fig. 7 is a section on line 7—7 of Fig. 6;

Fig. 8 is a section on line 8—8 of Fig. 6;

Fig. 9 is a plan view of the protecting wrapper with its absorbent edge; and

Fig. 10 is a bottom plan view of the heat insulating pad.

In proceeding in accordance with the present invention a clamp is employed which is composed of a main member 1 formed on its upper face with a depressed part which provides a semi-circular drip cup 2. A rod 3 is provided with a hand grip 4 and has a swivel connection 5 with a member 6 which latter is pivoted at 7 to a lug 8 that is carried by the member 1. A spring 9 carried by the post-like upper end of the member 6 engages the interior of the rod 3 and serves as a clutch to prevent retrograde movement thereof during

wrapping of the hair on the rod. The rod is preferably formed with spiral-like grooves 10 to provide a grip for the hair during wrapping on the rod, the hair being held in position by a coil spring 11 which is slidable on the rod and is provided with a finger grip 12. The rod is preferably divided as indicated at 13 and has a connection, similar to that of the swivel connection in Fig. 3 to facilitate wrapping of the hair on the rod. As shown in Figs. 2 and 5 the member 1 is of substantially U-shape and has its free ends formed with upper and lower spaced arms 14 and 15. A jaw 16 of U-shape in cross section is pivoted at 17 between the arms 14 and at its free end has a finger grip 18. The jaw is formed of spring metal and is provided with a knob 19 affording a latch which is adapted to be sprung into any one of three or more openings 20 carried by the upper of the arms 15 whereby to latch the jaw in hair clamping position. It will be noted that by the provision of three keepers 19 the latch may be sprung into any one thereof to clamp the hair in position, depending upon the amount of hair which is to be engaged by the clamp. The jaw 16 has a preferably rubber member 21 secured therein and which confronts a similar rubber member 22 that is held at its ends between the respective arms 14 and 15 as shown in Fig. 1. The rubber facing 21 of the jaw 16 is preferably roughened as illustrated at 23 in order to more effectively grip the hair.

The bottom of the member 1 is formed with an enlarged seating surface 24, from which the bottom of the drip pan or cup 2 is spaced, the latter also having a depending foot 25, the supporting surface as well as the foot being formed to engage a scalp-protecting pad composed of a rubber disc 26 secured to a preferably felt pad 27 as shown in Fig. 10. The scalp protecting or heat insulating pad is of circular shape and is formed with a key hole slot 28 through which the strands of hair to be waved or curled are projected, whereby the felt facing 27 will lie next to the scalp, while the rubber or water proofed facing 26 will form a seat on which the supporting surface 24 and the foot 25 will rest, thus affording a ventilating opening or passage 28 to maintain the clamp cool and increase comfort to the head of the user.

In use, with the hair next to the scalp clamped between the parts 21 and 22 of the clamp, and with the rod in the dotted line position of Fig. 1 at an incline to render easier the wrapping of the hair on the rod, turning of the rod, and thereby twisting of the hair thereon, results in the hair pulling against that part thereof held by parts 21 and 22 whereupon the rod is automatically moved to a position at substantially right angles to the clamp.

Referring to Figs. 6 to 8 a form of the inven-

115

110

120

tion is illustrated for use in upper right cro-quignole waving. In this form of the invention the clamping member 1' is in all respects similar to the clamping member depicted in Figs. 5 1 to 5 having the seat 24' and foot 25', but with the exception that a pair of spaced ears 29 project into the drip cup 2' in spaced relation to the bottom thereof and receive in the space between the ears the shank portions 30 of a bifurcated 10 head member 31, the shanks being carried by a member 32 to which the rod 33 is swivelled similar to the swivel as indicated in Fig. 4. With this construction it will be observed that the rod is readily attachable to and detachable from the 15 drip cup or pan. In this form of the invention a jaw or clamp 34 is pivoted at 35 to the rod 33 and at the inception of the waving operation the rod 33 is removed from the clamp and the latter is then applied in position on the head of the 20 wearer, following which, with the rod removed the hair is first clamped against the rod by the clamp 34 and is then twisted, and upon completion of the twisting operation the rod is applied to the clamp 1' by bringing the shanks 30 of the 25 member 32 into registry with the ears 29, whereupon the parts are slid into the position of Figs. 6, 7, and 8.

In Fig. 9 is illustrated a wrapper which is similar to that disclosed in my Patent 1,657,029, December 5, 1927, with the exception that the same is provided with a preferably flannel or other absorbent strip 37 at its lower edge which strip as depicted in Fig. 1 of the drawings when the pad is in position projects in the drip cup and acts 35 to absorb any products of condensation which may collect therein.

This wrapper is for use with both forms of the invention.

What is claimed, is:

40. 1. In combination with a clamp for holding the hair to be curled adjacent the scalp, a rod pivotally and turnably connected to the clamp, and means for holding the hair wrapped about the rod and with the latter initially at an incline to the clamp whereby upon turning of the rod the hair wrapped on the rod will pull against the portion thereof held by the clamp so as to effect movement of the rod to a position at substantially right angles to the clamp.
45. 2. In a hair curler or waver, a clamp having hair gripping parts and having a drip cup provided with liquid sealed bottom and sides formed on its outer face, a hair engaging rod connected to the clamp and a protecting member for the hair on the rod having an absorbent portion projecting in the drip cup.
50. 3. In a hair curler or waver for use with a protecting member for the hair having an absorbent portion, a hair clamp having a drip cup provided with liquid sealed bottom and sides, and a hair engaging rod having connection with the clamp and for receiving the protecting member over the hair wound on the rod and with the absorbent portion of the member extending into the drip cup.
55. 4. In combination with a clamp for holding the hair to be curled adjacent the scalp, a hair engaging rod associated with the clamp, means for holding the hair wrapped on the rod and with the latter initially at an incline to the clamp and means whereby to cause the rod upon twisting of the hair thereon to pull against the portion held by the clamp so as to effect movement of the rod to a position at substantially right angles to the 70 clamp.

5. In a hair waver or curler, a scalp protecting member having a part to receive therethrough the hair to be curled, a clamp having portions engageable with the member to hold the latter spaced from said member thereby to afford a ventilating passage, and a hair engaging rod carried by the clamp, said portions comprising an elongated part and a foot both of which parts seat against said member. 80

6. In a hair curler or waver, a clamp having a drip cup formed on its outer face provided with liquid sealed bottom and sides, a hair engaging rod removably connected to the clamp, a pivoted jaw carried by the rod to hold the hair thereon, and a protecting member for the hair on the rod having an absorbent portion projecting in the drip cup. 85

7. In a hair curler or waver for use with a protecting member for the hair having an absorbent portion, a hair clamp having hair gripping portions and having a drip cup having permanently closed sides and bottom, a hair engaging rod having a pivoted jaw and having a removable connection with the clamp and for receiving the protecting member over the jaw and over the hair 100 wound on the rod and with the absorbent portion of the member extending into the drip cup. 95

8. In combination with a clamp for holding the hair to be curled adjacent the scalp, a rod movably connected to the clamp, means for holding the hair wrapped about the rod and with the latter initially at an incline to the clamp, and means whereby upon winding of the hair wrapped on the rod the hair will pull against the portion thereof held by the clamp so as to effect movement of the rod to a position at substantially right angles to the clamp. 105

9. In a hair waver or curler, a clamp for holding the hair adjacent to the scalp, and a sectional rod swivelled to the clamp and having swivel 115 connections between its sections.

10. In a hair waver or curler, a clamp having a drip cup provided with liquid sealed bottom and sides, and a hair engaging rod connected to the clamp adjacent to the cup whereby products of 120 condensation will be received in the cup.

11. In a hair curler or waver, a scalp protecting member having a part to receive the hair to be curled, a hair clamping member having spaced lower parts for seating on the scalp protecting 125 member and having a drip cup on its upper portion, spacing means carried by the second member and engageable with the scalp protecting member to hold the drip cup spaced above the latter member, and means to clamp the hair in 130 the space between said lower parts of the hair clamping member.

12. In a hair curler or waver, a scalp protecting member having a part to receive the hair to be curled, a hair clamping member having parts for seating on the scalp protecting member and having a drip cup having closed sides and bottom on its upper side, spacing means carried by the clamping member and engaging the scalp protecting member to hold the bottom of the drip cup spaced above the latter member, and means to clamp the hair to said clamping member. 135

13. In a hair curler or waver, a scalp protecting member, a member having hair clamping means, a drip cup spaced in its entirety to one 140 side of the hair clamping means and a hair engaging rod connected to the clamping means. 145
